(57) **CLAIM**

The ornamental design for an air freshener device, as shown and described.

DESCRIPTION

FIG. 1 is an isometric view of a first embodiment of an air freshener device having a front housing, a translucent or transparent dome, and a rear housing;

FIG. 2 is a front view of the air freshener device of FIG. 1;
FIG. 3 is a back view of the air freshener device of FIG. 1;
FIG. 4 is a left view of the air freshener device of FIG. 1;
FIG. 5 is a right view of the air freshener device of FIG. 1
FIG. 6 is a top view of the air freshener device of FIG. 1;
FIG. 7 is a bottom view of the air freshener device of FIG. 1;

FIG. 8 is an isometric view of a second embodiment of an air freshener device having a front housing, a translucent or transparent dome, and a rear housing;

FIG. 9 is a front view of the air freshener device of FIG. 8;
FIG. 10 is a back view of the air freshener device of FIG. 8;
FIG. 11 is a left view of the air freshener device of FIG. 8;
FIG. 12 is a right view of the air freshener device of FIG. 8;
FIG. 13 is a top view of the air freshener device of FIG. 8;
and,

FIG. 14 is a bottom view of the air freshener device of FIG. 8.

The broken lines shown in the drawings are for illustrative purposes only and form no part of the claimed design.
